UNITED STATES PATENT OFFICE.

ANDREW J. KENNEDY, OF CHICAGO, ILLINOIS.

SKATE.

No. 922,774.

Specification of Letters Patent.

Patented May 25, 1909.

Application filed August 12, 1907. Serial No. 388,167.

To all whom it may concern:

Be it known that I, ANDREW J. KENNEDY, a citizen of the United States, residing at Chicago, in the county of Cook and State of Illinois, have invented certain new and useful Improvements in Skates, of which the following is a specification.

This invention relates to skates, and pertains more especially, although not exclusively, to roller skates.

One feature of the invention relates to a new and improved form and structure of ankle-brace designed to afford an ample and rigid lateral support for the ankle of the wearer, while permitting free forward and rear angular movement of the leg. This improvement is more particularly adapted for and useful in connection with skates having single front and rear wheels or rollers, or ice skates, wherein there is a greater lateral strain upon the ankle of the wearer than in the case of skates having four wheels or rollers, or ice skates having double runners.

Another feature of the invention resides in a new and improved yieldable support for the axles of the wheels or rollers adapted to permit a slight leaning movement of the wheel relatively to its supporting frame to facilitate travel around curves.

Another feature of the invention resides in the provision of a new and improved brake mechanism automatically actuated by the wearer when assuming a position favorable to arrest further travel, the brake mechanism being automatically applied by an angular movement of the leg above the ankle.

The invention will be readily understood when considered in connection with the accompanying drawings which illustrate a practical mechanical embodiment thereof, and in which,—

Figure 1 is a side elevational view of the complete skate shown as applied to the foot and lower leg portion of the wearer. Fig. 2 is a rear elevational view of the skate, more particularly illustrating the form and character of my improved ankle-brace. Fig. 3 is a sectional view and on an enlarged scale through one of the journals of the wheels. Fig. 4 is a detail plan view of a sheet metal blank from which the housing of each end journal of the wheels is made.

Referring to the drawing, 10 designates as

an entirety a skeleton frame for the skate consisting of duplicate side members, between and on which are supported the heel-plate 11 and toe-plate 12, which latter may be formed integral with or suitably secured to the main frame.

13 and 14 designate, respectively, single front and rear wheels or rollers that are journaled by means and in a manner more particularly described between the front and rear depending forks of the skate-frame and in the longitudinal median plane of the 65 skate, as best shown in Fig. 2. Each of these wheels, which are of relatively large size as compared with the wheels or rollers ordinarily employed on skates of this character, is preferably equipped with a rubber tire 70 15, the web and hub of the wheels being conveniently formed of suitable stamped metal disks which may be solid or of skeleton form as preferred.

Referring now to the improved ankle-brace constituting a leading feature of my invention, this member is designated as an entirety by 16 and preferably, and as herein shown, consists of a single or one-piece sheet metal stamping of sufficient thickness 80 to possess the required rigidity, comprising an approximately semi-circular horizontal strap 16^a at its upper end adapted to embrace the rear portion of the leg of the wearer slightly above the ankle or approximately at the base of the calf, and a rigid depending member 16^b connected with the upper strap 16^a by inclined branches 16^c and having depending oppositely inclined limbs or branches 16^d that are pivoted at 90 17 to the upper ends of the skate-frame on either side of the latter and at points substantially opposite the ankle of the wearer. The central transversely extending portion of the brace-member 16^b is concave on its 95 inner side to fit the convex rear portion of the leg, and the inclined arms or branches 16^c and 16^d lie obliquely across the opposite sides of the leg as shown. To the front edges of the upper collar or strap 16^a are 100 riveted or otherwise secured short leather straps 18, the forward edges of which may be united, when the skate is applied, by a lacing 19 or other suitable means, whereby the brace is securely applied or attached to 105 the leg of the wearer.

I am aware that ankle-braces pivoted to the upper ends of the skate-frame and adapted to be secured to the leg of the wearer are broadly old, but experience has demonstrated to me that a brace of this character is practically useless unless it is rigid and unyielding against lateral movement relatively to the skate-frame. So far as I am aware such braces as have heretofore been proposed or employed consist of independent side members pivoted to the respective sides of the skate-frame and at their upper ends secured to the leg of the wearer. In such cases, the two side-braces being independent of each other, little or no lateral rigidity is afforded.

It will be observed as a distinguishing characteristic of my improved ankle-brace that the two sides thereof are rigidly united behind the leg either by making the brace from a single stamping, as indicated, or rigidly connecting the two sides, so that the two sides are mutually braced through the intervening transverse connections against any lateral yield or bend relatively to the skate-frame, and hence the entire leg from the lower calf portion to the foot is supported against transverse bend at the ankle while at the same time the free forward and rear bend at the ankle is permitted.

Referring next to my improved manner and means of mounting the wheels of the skate in the frame whereby the wheel may lean laterally to adapt itself to the desired direction of movement, and more particularly considering Figs. 3 and 4 of the drawings wherein the details thereof are shown, 20 may designate the hub of the wheel in which are formed suitable race-ways for ball-bearings 21. 22 designates the axle that extends through the hub preferably in engagement with a hard metal sleeve or bushing 23. The lower ends of the forks of the skate-frame indicated by 10^a are longitudinally slotted from their lower ends upwardly to a sufficient distance to receive bearing-blocks 24. Each of these bearing-blocks has formed on its inner edge, which enters the hub 20 of the wheel, a suitable race-way engaged by the ball-bearings 21, and one of said bearing-blocks preferably has a screw-threaded engagement with the axle 22 whereby adjustment of the ball-bearings may be readily effected. The opposite sides of the bearing-blocks 24 are recessed or grooved to a sufficient extent to admit the block within the slot of the fork, and said grooves are widened on both sides of the center of the side walls thereof, thereby forming rocking 60 bearings indicated at 25, which permit a tipping or angular movement of the axle and bearing-block to a limited extent. Secured to the outer sides of and beneath the forks 10^a of the frame are brackets through which 65 the weight is transmitted to the bearing-

blocks and axle, which brackets also constitute the housings for the ends of the bearing-blocks and the superposed means, hereinafter described, for permitting a tipping or angular movement of the axle and restoring it to normal position. Each of these brackets or housings is preferably made from a single sheet metal blank of the form shown in Fig. 4, the same consisting of a main body 26, a leaf 27 thereabove, a central tongue 28 and side tongues 29 above said leaf 27, a narrow leaf 30 below the leaf 26, another narrow leaf 31 below the leaf 30, and side wings 32 on either edge of the body 26. This blank is cut and bent to form the complete 70 housing as follows. The tongues 29 are separated on vertical lines from the central tongue 28, which latter is bent down beneath and parallel with the leaf 27, the leaf 27 is then bent at right angles to the body 26, and 75 the outer tongues 29 are bent upwardly to be secured to the side of the fork 10^a, as shown in Fig. 3. The central tongue 28 and leaf 27 are provided with registering apertures that are internally threaded to receive an adjusting device in the form of a screw-threaded pin 33. The body 26 is bent on a substantially central transverse line to form a lower inclined portion 26^a of the housing, the leaf 30 is bent to horizontal position to lie directly beneath the lower end of the fork, and 80 the lower leaf 31 is bent upwardly to engage behind the lower end of the fork, thereby securing the housing to the fork at its lower end. The side wings 32 are then bent at 85 right angles to the body 26 to form the side walls of the housing and complete the inclosing of the contained parts. The bearing-blocks 24 have outwardly projecting flanges 24^a, above which and within the housings 105 are mounted yieldable resilient elements which may be ordinary compression springs, but preferably consist of blocks of rubber 33^a. Thin metal wearing plates 34 and 35 are preferably interposed between the lower 110 and upper faces of the rubber blocks and the flanges 24^a and adjusting screw-pins 33, respectively. From the foregoing it will be seen that the weight of the wearer is transmitted from the fork to the axle through the 115 brackets or housings, the screw-pins, the rubber-blocks, and the bearing-blocks. By virtually hooking the lower ends of the brackets or housings beneath the lower ends of the fork, as shown, the strain on the upper 120 connections of the bracket to the fork is largely relieved; and by reason of the fact that the slots of the fork extend inwardly beyond the upper sides of the bearing-blocks, as indicated in Fig. 1, the wheel and its axle 125 are free, under lateral strain, to tip or incline in either direction as may be required by the movement of the operator, the rubber blocks 33^a yielding to permit the same and automatically restoring the wheel to normal position. 130

tion when the foot is raised or restored to vertical position.

In connection with the above-described skate I have provided a simple and economical form of brake mechanism enabling the wearer to arrest further movement upon assuming a certain position of the lower limbs. Referring thereto, 36 designates a brake-shoe herein shown as applied to the rear 5 wheel, the same being pivoted between the sides of the frame substantially opposite the heel-plate. The brake-shoe has upwardly extending arms 37, the upper ends of which are connected to depending extensions 16° 10 of the ankle-brace by pivoted links 38. In the arrangement of mechanism shown in Fig. 1 it will be seen that the rearward inclination of the leg above the ankle will apply the brake-shoe to the rear wheel. The wearer, 15 in assuming a position favorable for stopping without danger of falling headlong from acquired momentum, naturally throws one foot in advance of the other, bending the lower portion of the forward leg rearwardly 20 and the lower portion of the rear leg forwardly. Consequently, on the other skate the brake-shoe 36 will incline rearwardly or on the opposite side of the pivot so that it 25 will be applied under a forward bending 30 movement of the leg of the wearer.

From the foregoing it will be seen that my invention provides a simple, strong, durable, and easily operated article of the character described. The frame and brace parts can 35 readily be made from metal stampings, thus conducing to the economy of the device, and the lateral rigidity afforded to the ankle of the wearer by the rigid ankle-brace conduces to the comfort and ease with which the 40 skate may be worn and operated.

It will be evident to those skilled in the art that variations and modifications in respect to minor details of structure may be made without departing from the substance or 45 sacrificing any of the advantages of the invention; and hence I do not limit the latter to the particular construction disclosed, except to the extent clearly indicated in specific claims.

50 I claim:

1. The combination with a skate having a pair of side-frame members, of an ankle-brace pivoted to said side-frame members and adapted to partially embrace the leg of the wearer, said ankle-brace being transversely rigid relatively to said side-frame members, substantially as described.

2. The combination with a skate having a pair of side-frame members, of a rigid one-piece ankle-brace pivoted to said side-frame members and adapted to partially embrace the leg of the wearer, substantially as described.

3. The combination with a skate having a 65 pair of side-frame members, of a transversely

rigid ankle-brace having a portion adapted to partially embrace the leg of the wearer and depending extensions lying on opposite sides of the leg and pivotally connected to said side-frame members, substantially as described. 70

4. The combination with a skate having a pair of side-frame members, of an ankle-brace comprising an upper portion adapted to partially embrace the leg of the wearer, 75 depending extensions lying on opposite sides of the leg and pivotally connected to said side-frame members, and a transversely disposed portion connecting said depending extensions, all of said parts being rigidly joined 80 together, substantially as described.

5. In a wheeled skate, the combination with a longitudinally slotted fork, of a wheel having an axle projecting through the slots of 85 said fork, springs supported on the projecting ends of said axle, and brackets secured to the sides of said fork and bearing on said springs, substantially as described.

6. In a wheeled skate, the combination with a longitudinally slotted fork, of a wheel 90 having an axle projecting through the slots of said fork, bearing blocks mounted on the ends of said axle and having rocking bearings engaging the slotted sides of said fork, 95 springs bearing on said bearing blocks, and brackets secured to the sides of said fork and bearing on said springs, substantially as described.

7. In a wheeled skate, the combination with a longitudinally slotted fork, of a wheel 100 having an axle projecting through the slots of said fork, bearing-blocks mounted on the ends of said axle and having rocking bearings engaging the slotted sides of said fork, springs bearing on said bearing blocks, brackets secured to the sides of said fork, and screw-threaded pins mounted in said brackets and 105 engaging said springs, substantially as described.

8. In a wheeled skate, the combination 110 with a longitudinally slotted fork, of a wheel having an axle projecting through the slots of said fork, bearing blocks mounted on the ends of said axle in the slotted sides of said fork and having rocking bearings engaging 115 said slotted sides of the fork, rubber-blocks supported on said bearing-blocks, brackets secured to the sides and lower ends of said fork and inclosing said rubber-blocks and the projecting ends of said bearing blocks and 120 axle, and screw-threaded pins mounted in said brackets and engaging said rubber-blocks, substantially as described.

9. In a wheeled skate, the combination with the skate frame, of a brake-lever for 125 one of the wheels pivoted on said frame, an ankle-brace also pivoted on said frame, an arm carried by said ankle-brace, and a link pivotally connecting said arm and brake-lever whereby an angular movement of said 130

ankle-brace in one direction applies the brake and in the opposite direction releases the brake, substantially as described.

10. In a wheeled skate, the combination with the skate frame, of a brake-lever for one of the wheels pivoted on said frame, an ankle-brace pivoted to the upper ends of the sides of said frame, an arm rigid with said

ankle-brace and depending below the pivotal point thereof, and a rigid link pivotally joined at its ends to said arm and brake-lever, respectively, substantially as described.

ANDREW J. KENNEDY.
